Application filed March 19, 1901. Serial No. 51,940. Term of patent 14 years.

To all whom it may concern:

Be it known that I, FRED L. DAGGETT, a citizen of the United States, residing at Somerville, county of Middlesex, and State of Massachusetts, have invented and produced a new and original Design for a Tray for Display of Confectionery, of which the following is a specification, reference being had to the accompanying drawings, forming part thereof, in which—

Figure 1 is a perspective view of a confectionery display-tray embodying my new design. Fig. 2 is a central transverse section of the same.

The material features of my design are the

rectangular shallow body and the projection extending outwardly from the bottom of the tray and deflected into a position inclined to the front of the tray and provided on its front face with lips or lugs, substantially as shown.

Having thus described my invention, what I claim as new, and desire to secure by Letters Patent, is—
